UNITED STATES PATENT OFFICE.

RUSSELL S. PATERSON, OF MOBILE, ALABAMA.

METHOD OF PREPARING TANNIC-ACID COMPOSITIONS.

No Drawing.

Application filed February 4, 1926. Serial No. 86,061.

My invention relates to a medical compound and method of making the same.

The object of my invention is to provide a medical compound for internal use by injection and one that is especially adapted to be used in the treatment of gonorrhea, gleet and their complications.

The ingredients of the compound are tannic acid, zinc oxide, glycerin and water and the preparation may be made in two strengths by increasing or decreasing the amount of tannic acid and zinc oxide used.

A full strength compound consists of:

15	Tannic acid	2½ drams
	Zinc oxide	2½ drams
	Glycerin	2 fluid ounces
	Distilled water	5 6/16 fluid ounces

20 A medium strength compound is composed of:

25	Tannic acid	2 drams
	Zinc oxide	2 drams
	Glycerin	2 fluid ounces
	Distilled water	5½ fluid ounces

The preferred method of making the medical compound is as follows:

30 Tannic acid and zinc oxide are thoroughly ground and mixed together by stirring for a considerable length of time. Glycerin is then added and the same stirred until the ingredients are thoroughly mixed; a small portion of distilled water is then added and the whole mass given two or three stirs in the same direction and the mass allowed to stand until it sets. The hardened mass thus formed is redissolved in distilled water to produce a compound by volume of approximately 8 35 ounces.

40 If the mass first formed does not harden or set, it is thrown away, as unless the mass first produced hardens, I have found that the compound does not have the same qualities.

45 In producing a full strength compound in accordance with my method of making the same, I take 5/16 ounces of tannic acid and 5/16 ounces of zinc oxide and grind and mix these thoroughly together and to this mixture

I add 2 fluid ounces of glycerin and the whole 50 mass is stirred thoroughly. I then add 1 8/16 fluid ounces of distilled water and give the mass two or three stirs in the same direction. The mass is then let stand until it sets and after it has set, it is redissolved in substantially 3 and 14/16 fluid ounces of distilled water, which produces a compound by volume of approximately 8 ounces.

In carrying out the method to produce the medium strength, 1/4 ounce of tannic acid 60 is mixed with 1/4 ounce of zinc oxide by thoroughly grinding and stirring the two together and to this mixture 2 fluid ounces of glycerin is added and the whole mass stirred thoroughly. I then add 1 1/2 fluid ounces of 65 distilled water and stir the same two or three times in one direction only and the mass thus formed is allowed to stand until it sets or hardens. After the mass has hardened, it is redissolved in 5 1/2 fluid ounces of distilled 70 water, which produces a compound by volume of approximately 8 ounces.

The medicine is used as an urethral injection from two to four times a day, using it four times a day at the start and gradually 75 cutting the injection to two as the gonorrhea gets better. It can be injected with any ordinary urethral syringe by the patient himself or can be injected by the doctor.

The dosage will vary according to the size 80 of the urethra. Enough is injected to fill the urethra until the patient can just feel the solution entering the bladder and this as a rule takes from two to three drams.

85 While I have described a method of producing a medical compound for the treatment of certain diseases, it is, of course, understood that the same can be used for treating kindred diseases and that the proportions can be varied without departing from the spirit of 90 my invention.

What I claim is:—

1. The method herein described of making a medical compound from tannic acid, zinc oxide, glycerin and distilled water, which 95 consists in grinding and mixing together tannic acid and zinc oxide, then mixing glycerin with the compound produced, then add-

ing distilled water and allowing the mass to harden, then redissolving the hardened mass in distilled water.

2. The method herein described of making a medical compound from tannic acid, zinc oxide, glycerin and water consisting in thoroughly grinding and stirring tannic acid and zinc oxide together, adding glycerin and

again thoroughly stirring the ingredients then adding distilled water and slightly stirring the water into the mass and allowing the mass to harden and then redissolving the hardened mass in distilled water.

In testimony whereof I hereunto affix my signature.

RUSSELL S. PATERSON.
